US00D867302S

(12) **United States Design Patent** (10) **Patent No.:** **US D867,302 S**
(45) **Date of Patent:** **** Nov. 19, 2019**

(54) **ADAPTER**

- (71) Applicant: **Cheng Uei Precision Industry Co., Ltd.**, New Taipei (TW)
- (72) Inventors: **Feng Zhu**, Dong-Guan (CN); **Xing-Yu Hu**, Dong-Guan (CN); **Gao-Hua Du**, Dong-Guan (CN)
- (73) Assignee: **CHENG UEI PRECISION INDUSTRY CO., LTD.**, New Taipei (TW)

(**) Term: **15 Years**

(21) Appl. No.: **29/632,298**

(22) Filed: **Jan. 5, 2018**

(30) **Foreign Application Priority Data**

- Nov. 21, 2017 (TW) 106306795
- (51) **LOC (12) Cl.** **13-03**
- (52) **U.S. Cl.**
USPC **D13/147**
- (58) **Field of Classification Search**

(57) **CLAIM**

The ornamental design for an adapter, as shown and described.

DESCRIPTION

FIG. 1 is a perspective view of an adapter showing our new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof;

FIG. 7 is a bottom plan view thereof; and,

FIG. 8 is another perspective view of the adapter showing our new design.

The broken lines are directed to environment and are for illustrative purposes only; the broken lines form no part of the claimed design.

1 Claim, 8 Drawing Sheets
